UNITED STATES PATENT OFFICE

HENRY ELDRIDGE, OF TORONTO, ONTARIO, CANADA.

FEATHER-RENOVATOR.

SPECIFICATION forming part of Letters Patent No. 324,463, dated August 18, 1885.

Application filed April 23, 1885. (No model.)

To all whom it may concern:

Be it known that I, HENRY ELDRIDGE, a subject of Her Majesty the Queen of Great Britain, and residing at the city of Toronto, 5 in the county of York, Province of Ontario, and Dominion of Canada, have invented a new and useful Improvement in Feather-Renovators, of which the following is a specification.

10 My invention relates to feather-renovating devices, and is an improvement therein.

The object of my invention is to provide a more complete and satisfactory device than those heretofore produced. These objects I 15 accomplish in the manner and by the mechanism illustrated in the accompanying drawings, in which—

Figure 1 is a top view of the device, with portions broken away so as to illustrate the 20 position of the steam-chamber V, inlet f, and outlet h, and ventilating-door e d. Fig. 2 is a side view of the same device, and having also portions of it broken away so as to further illustrate steam-chamber V, tick-filling device m, steam-pipes S', and steam-chambers V', together with agitating device W'. Figs. 25 3 and 4 are end views of the same device, further illustrating the location of the several steam-pipes. Fig. 5 is a cross-section of the same device and in the line x y of Fig. 2, and 30 illustrates the position of the guard g, ventilating-door t r, steam-pipes S', slide-door c, and agitating-wings W'. Fig. 6 is a top view of A' with a portion of O broken away, and 35 further illustrates the location of the steam-pipes S' and steam-chamber V'.

Similar letters refer to like parts in all the figures.

Heretofore it has been common to employ 40 steam in renovating feathers; but the devices heretofore proposed or produced have been, so far as I am aware, crude and defective, not only as regards the renovating of the feathers, but also in the methods and manner of drying them. These objectionable features are overcome by the device here illustrated.

This device may be operated by hand or by other power. h represents a winch, and W a pulley-wheel, and W' are the agitating-wings 45 which they are designed to operate.

A is the upper half of the device, and is distinct and separate from the lower half, A'.

V is a steam-chamber occupying a portion of the top of A (see Fig. 5) and the whole of each end of A. (See Fig. 1.)

55 e d and t r are ventilating-doors, composed of wire-gauze and tin, t and e representing the tin and d and r the wire-gauze. One of these doors is located at the top of A, (e d,) and the other at the side.

60 g is a metallic shield or awning, designed to direct downward the escaping dust from the feathers. c is a slide-door controlling the chute m.

65 In the lower half of the device, A', are located two steam-chambers, V' V'—one at each end of A'—and these are connected by steam-pipes S'. Over these is a metallic shield, O, which forms the floor of the feather-chamber, within which W' is revolved. This shield is 70 perforated at one end, so as to admit within the feather-chamber the steam direct from the pipes q and p.

75 n, u, and l are pipes, leading to and from the chambers V' and V', and k and f are steam-pipes leading to and from the steam-chambers V in the upper half of the device.

S is any suitable foundation for sustaining and supporting the whole device.

80 The operation of the device is as follows, viz: The doors t, r, and c being closed, the feathers are introduced through the door e d to the chamber occupied by the agitating device W'. e d is then closed, and steam from the pipes q p is admitted directly upon the 85 feathers, and they are meanwhile agitated by W' until cleansed. The tin doors t and e are then thrown open and steam admitted to the drying or steam chambers V and V' through the pipes u and f, and the steam-pipes q and 90 p are closed by means of a cock, (with which all pipes are provided.) The feathers are then

95 agitated as before and subjected to hot air produced within their chamber by means of the steam-chambers V and V'. This hot air, together with the ventilating current through the screen-doors d and r not only dries the feathers, but throws the impurities driven off from them out through the door r, while the space within the chamber and above the agitating device is sufficient to permit every fiber of the feathers to expand and assume their original proportions, and when sufficiently dried the door c is opened and the greater 100

portion of the feathers may be forced through *m* into their proper tick or container by means of *W*.

With the above description and the accompanying drawings it is believed that any person skilled in the art to which this invention appertains could readily construct and use the same.

I am aware that it has been heretofore proposed to construct feather-renovators having a revolving beater located within a drum, said drum having a steam-jacketed bottom and pipes for admitting steam into the body of the drum, and having a cover provided with 15 ventilating-openings. I do not claim, broadly, such combination of parts.

What I claim, therefore, and desire to secure by Letters Patent of the United States, is—

In a device for renovating feathers, the combination of the receptacle *A'*, provided with 20 steam-drums at each end thereof, with connecting-pipes *S* between said drums, the shield or apron *O*, located over said drums and pipes, the cover *A*, provided with a steam-chamber, *V*, at each of its ends and extending over a 25 portion of its top, pipes for the admission of steam connected with the several steam-chambers, an agitator, *W'*, and ventilating-ports *r* and *d*, covered with wire net-work and located, respectively, in the side and top of the 30 cover.

HENRY ELDRIDGE.
